UNITED STATES PATENT OFFICE.

HENRY P. MERRIAM, OF NEW YORK, N. Y.

FUSE FOR PROJECTILES.

SPECIFICATION forming part of Letters Patent No. 770,183, dated September 18, 1904.

Application filed July 18, 1902. Renewed July 16, 1904. Serial No. 216,778. (No model.)

To all whom it may concern:

Be it known that I, HENRY P. MERRIAM, a citizen of the United States, residing in the borough of Manhattan, in the city and State 5 of New York, have invented certain new and useful Improvements in Fuses for Projectiles, of which the following is a specification.

The present invention, which relates to improvements in percussion-fuses for projectiles, has for its object the prevention of the premature functioning of the fuse and the thereby caused explosion of the shell during the flight of the shell and up to the time of impact of the shell upon the target.

In the type of projectile-fuses in which the detonating-hammer is released or armed in the fuse-casing by the shock caused by the firing of the projectile from the gun or by the centrifugal force developed by the rapid rotation 20 of the shell during its flight some difficulty has been experienced in effectually delaying the explosion of the shell until the shell has struck the target. In the normal action of fuses of this type the explosion of the shell after firing is effected by the forward or, in special designs also, by the sidewise displacement of the hammer, (which has been released or armed in the fuse-casing and is held only by inertia or a light spring in its central rear- 25 ward position therein,) said forward or sidewise displacement of the hammer causing the hammer or the firing-pin to detonate the primer. This sidewise or forward displacement of the hammer is produced when the shell operates properly by the impact of the shell either endwise or sidewise against the target. On account of mechanical imperfections, however, which must necessarily be considered, there is lack of coincidence between 30 the axis of rotation of the shell and the center of gravity of the hammer, with the result that the equilibrium of the hammer in the fuse-casing is disturbed and the hammer is displaced more or less in its casing laterally and forwardly. If the displacement is sufficient to force the hammer forward with sufficient force, as is frequently the case, the primer will be detonated and the shell exploded during the flight of the shell and before it reaches the 35 target.

The present invention consists in providing means for automatically retaining the hammer in its central rearward position in the fuse-casing during the flight of the projectile and up to the time of impact on the target. The 5 means for accomplishing this result comprise centrifugally-operated retaining arms or weights.

Any disturbing or displacing force which acts upon the freely-supported hammer during the flight of the shell is proportional 10 to the square of the velocity of rotation of the shell, and the correcting force—that is, the force of the centrifugally-operated retaining arms or weights acting upon the hammer—being also proportional to the square of velocity of rotation of the shell is proportional 15 to the disturbing force and with suitably-proportioned arms or weights can be made to at all times exceed the disturbing force. It is 20 possible to correct this disturbing tendency 25 entirely by the use of springs adjusted to the conditions contemplated; but springs are objectionable for many reasons, but principally because their constant elasticity cannot be depended upon, and this method, moreover, would 30 not be applicable to a fuse adapted to widely-different sizes of shell without sacrificing the 35 sensitiveness required in the larger and slower rotating shells, while guarding sufficiently 40 against premature explosion in the smaller 45 shells.

It is of considerable importance that the number of different sizes and types of fuses covering the various-sized shells be made as few as possible, and with this in view a medium-sized fuse must have for service in the largest shells the maximum sensitiveness, represented by a very sensitive primer, acted upon by a hammer whose force at impact is as little as possible retarded by friction or a retaining-spring. For the smaller shells the extreme sensitiveness of primer is not necessary; but here it is necessary to guard the hammer against forward movement by a greater retaining force, which were it applied in the 55 case of the large shell would interfere with the sensitiveness there required. As the range of action which it is sought to cover in this 60 form of fuse would vary from a shell rotating perhaps one thousand turns per minute to one 65

rotating fifteen thousand turns per minute, the centrifugal force has a range of from one to two hundred and twenty-five—i. e., in the ratios of the squares. While this force is considerable at the higher rotation, it is also small at the lower rotation, and for large shells at the lower limit it is possible that the centrifugal force may need to be supplemented by springs acting in conjunction with the centrifugal arms or weights. It is obvious that the springs and centrifugal arms or weights can be arranged singly or in multiple, as the case may require. These arms or weights may be arranged to act directly upon the hammer to retain it in its rearward or inactive position during the flight of the shell, or they may act through the medium of springs, in which case they will simply tend to increase the tension of the springs, and in this latter case the limit of the maximum force with which the hammer is restrained can be determined by the limit of travel permitted to the retaining arms or weights. It is thus possible by combining the centrifugal force of the arms or weights adjusted for any determined maximum limit with supplemental springs which would increase the retaining force more effectively at the slower rotation to get any adjustment of retaining forces desired, all varying with the character of service under which the fuse happened to be used.

There are numerous forms in which this invention may be worked out; but the principle involved is the same in all cases, and it is that which I wish to cover broadly in my present case.

As illustrating two forms of projectile-fuses to which the present invention may be applied I would refer to my Patent No. 630,622, granted August 8, 1899, and my pending application, originally filed March 30, 1901, renewed January 4, 1902, renewal Serial No. 88,444.

I have illustrated my present invention as applied to the form of fuse covered by my renewal application, renewal Serial No. 88,444; but I do not limit myself to this application of the invention, but desire to claim the invention in a broad sense without reference to the form of fuse to which it is applied.

In order that my invention may be fully understood, I will first describe the same with reference to the accompanying drawings and afterward point out the novelty more particularly in the annexed claims.

In said drawings, Figure 1 is a longitudinal sectional elevation of a fuse embodying my invention. Fig. 2 is a transverse sectional view of the same, taken on the line $a-a$ of Fig. 1. Fig. 3 is a detail view similar to Fig. 1, showing a modified form of my invention. Fig. 4 is an inside end elevation of the fuse-head as it appears when removed from the hammer-supporting or main portion of the fuse-body. Fig. 5 is a detail sectional view illustrating one of the centrifugally-operated arms or weights of the form shown in Fig. 3.

Figs. 6 and 7 are detail views similar to Fig. 1, showing further modifications of my invention.

My present improvement in fuses is applicable to any form of percussion-fuse in which the detonating-hammer is released in the fuse-casing at the time of firing the shell from the gun or during the flight of the shell, whether the fuse be designed for a "point-fuse" or a "base-fuse." In the drawings the invention is shown as applied to a base-fuse.

1 is the body of the fuse, externally threaded at 2 for screwing into a shell.

3 is the head of the fuse, carrying the primer, firing-pin, and the centrifugally-operated controlling devices.

The body 1 is formed with a cavity 5, having a seat or recess 6, in which normally rests the ball-shaped hammer 7.

The head 3 is formed with a central longitudinal cavity 10, in which is movably mounted the combined firing-pin and hammer-securing pin 11. This firing and hammer-securing pin 11 is formed with an annular shoulder 12, with which engage the inner shouldered ends of the radially-movable bolts or pistons 15, which are supported in the sockets 16, radiating from the central recess or passage 10. The bolts or pistons 15 fit snugly together at their inner end and have an opening 17 formed through their adjacent end walls for the passage of the reduced portion of the firing and securing pin 11. Projecting from each bolt or piston 15 is a pin or rod 18, which extends from the bolt or piston at an angle of thirty degrees to its longitudinal axis and fits and slides in a socket 19, formed in an adjacent bolt or piston and extending at an angle of thirty degrees to the longitudinal axis of its bolt or piston. Each bolt or piston 15 of the series of three has a pin or rod projecting from it and secured to it, as described, and each bolt or piston is also formed with an angularly-extending socket 19, into which one of the pins or rods projects, as described. Lateral cuts or recesses 20 are formed in the wall of the central opening 10 of fuse-head 3 to permit the lateral movement of the pins or rods 18 when the bolts or pistons move outwardly simultaneously. It will be clear that any movement of one of the bolts or pistons individually will be resisted by the pins 18, connecting said piston with the other two pistons. When, however, the bolts or pistons move simultaneously under the centrifugal force of the rapidly-revolving shell, it will be observed that the movement of the bolts or pistons at an angle to each other will allow for the lateral movement of the connected pins or rods, and the bolts or pistons will therefore move freely in their sockets to release the hammer-securing pin 11. This construction and its operation are fully explained and claimed in my above-named application, renewal Serial No. 88,444.

Mounted in the upper end of the central

opening or socket 10 is the primer 25, which is of course supported on the usual anvil. The end of the primer 25 rests just above the pointed end of the firing-pin, so as to be effectively detonated when the firing-pin is forced against it. The primer 25 is arranged to flash into and ignite a small magazine of powder 26, contained in the recess 27, formed in the end of the fuse-head 3, a cap of thin sheet metal 28 covering the recess 27 for retaining the powder therein. It will be understood by those skilled in the art that when the powder 26 is ignited the cap 28 will be blown off and the fire therefrom transmitted to the bursting charge of the shell.

With this form of fuse it will be clear that the centrifugally-operated bolts or pistons 15 will be moved outwardly to release the firing and securing pin 11 immediately after the shell has left the gun. The firing-pin will then be free to move forwardly in the fuse-head and the hammer will be freed to the objectionable disturbing or displacing force above referred to, thereby subjecting the shell to the danger of a premature explosion. My present invention obviates this danger, as above pointed out, in the manner which I will now describe.

Referring now to Figs. 1 and 2 of the drawings, 35 is a socket or recess drilled into the fuse-head 3 at an angle to its longitudinal axis. This socket 35 opens at the inner end of the fuse-head and also cuts through the threaded wall 4 for the purpose which will presently appear. 40 is an arm or weight loosely resting in the inclined socket 35. This arm or weight 40 is formed with a spherical head 40^a, which rests in the similarly-shaped upper end of the socket 35. The arm or weight 40 is also formed with a nose or shoulder 40^b, which projects beyond the threaded wall 4 of the fuse-head 3 and engages the inner end of the main fuse-body 2 for loosely confining the arm or weight 40 in its socket. A pin or rod 45 projects from the inner free end of the arm or weight 40 and extends at an angle therefrom across the central longitudinal axis of the fuse, where it rests directly above the hammer 7. The hammer-engaging end of the securing-pin 11 is slotted at 11^a to allow for the passage and free movement of the hammer-engaging pin or rod 45. The inner face of the fuse-head 3 is slotted at 3^a to receive the hammer-engaging pin or rod 45 for the purpose of avoiding interference with the stroke of the hammer upon the firing-pin at the moment of impact of the projectile upon the target.

It will be observed that after a shell equipped with my improved fuse has left the gun and is rapidly revolving during its flight the centrifugal force acting upon the hammer-retaining arm or weight 40 will tend to throw the arm or weight outwardly, and thereby move the pin or rod 45 into engagement with the hammer 7 with more or less power, depend-

ing upon the rapidity of rotation of the shell during its flight. The hammer during the flight of the shell is free from the restraint of the securing-pin 11 and controlling bolts or pistons 15, but is held securely in its seat by the engagement of the pin or rod 45, projecting from the centrifugally-operated weight 40. When the projectile strikes the target, the pin or rod 45 of the centrifugally-operated weight 40 immediately releases the hammer by reason of the arresting of the centrifugal action, and the hammer is forced forwardly in the socket of the fuse-body into engagement with the firing-pin, thereby detonating the primer and exploding the shell. When the hammer moves forwardly in its cavity at the impact of the shell, the pin or rod 45 moves into the slot or recess 3^a, and thereby gets out of the way of the hammer to expose the firing-pin to the full stroke of the hammer.

In Figs. 3, 4, and 5 I have shown a slight modification in which I employ a series of three centrifugally-operated arms or weights for retaining the hammer in its seat after the securing-pin 11 has been released and during the flight of the shell. In this form of the device the fuse-head 3 has cut into its inner end the slots 50, which are inclined to the longitudinal axis of the fuse. Loosely supported in these inclined slots 50 are the hammer-retaining arms or weights 51, each one of which is provided with a retaining-shoulder 51^a, that is engaged by the inner end of the fuse-body 2, and a hammer-engaging nose 51^b, which rests between the hammer 7 and the inner end of the hammer-retaining pin 11. The inner adjacent ends of the arms or weights 51 are so shaped that they will not interfere with each other in their action. A light wire spring 53 is secured at one end in a socket 54, extending radially into the fuse-head 3, and rests in a groove 55, formed in the under face of one of the arms or weights 51. A spring 53 is provided for each of the arms or weights 51. The operation of this modified form of the device is practically the same as in the preferred form above described.

In Fig. 6 I have shown a further slight modification in which a spring-arm 60 is pivoted to the fuse-head 3 at 61 and is supported thereby to move freely in the radial cut or recess 62. A weight 63 is mounted upon the spring-arm 60. The arm 60 projects across the central longitudinal axis of the fuse, passing through the slotted inner end of the hammer-securing pin 11, and engages the hammer 7. The centrifugal force acting upon the weight 63 causes the spring-arm 60 to hold the hammer 7 in its seat during the flight of the shell, substantially as above described in connection with the other forms of the device.

In Fig. 7 I show a form of the invention applied to a fuse having a different-shaped hammer. In this form of the fuse the seat or recess 6^a at the end of the hammer-containing

cavity 5 is of conical shape, and the hammer 7^a has its end of corresponding shape to fit in said seat or recess. The hammer has a cone-shaped recess 70 at its inner end, in which 5 engages the cone-shaped end of the hammer-securing pin 11^a. This form of hammer is particularly designed to produce an effective side-acting fuse, so that when the shell strikes upon one side the sidewise displacement of the 10 hammer will effectively force the firing-pin forwardly to detonate the primer. The securing-pin is held in its locked or hammer-securing position by the same means as above described.

15 To prevent the objectionable displacing of the hammer in the cavity of the fuse during the flight of the shell, I provide inwardly bowed spring-arms 75, which rest in the longitudinal cuts or recesses 76 of the hammer 20 and carry the small weights 77. These spring-arms 75 engage the fuse-head 3 at one end and the undercut shoulders 78 of the hammer at their opposite ends. During the flight of a shell equipped with this form of fuse it will 25 be clear that the centrifugal force acting upon the weights 77 will tend to straighten out the spring-arms 75 and hold the hammer in its seat against any disturbing force which it may be under the influence of.

30 I desire to claim, broadly, a centrifugally-operated hammer-retaining device for the purpose above specified. I also desire to claim such a centrifugally-operated device in combination with a fuse having a hammer and 35 means for automatically releasing the hammer in the fuse-chamber before or during the flight of the shell. I also desire to claim such a centrifugally-operated hammer-securing device in combination with centrifugally-operated 40 means for releasing the hammer in the fuse-casing.

Having thus described my invention, the following is what I claim as new therein and desire to secure by Letters Patent:

45 1. In a fuse for projectiles, the combination of a fuse-body, and a hammer supported in the fuse-body, with a hammer-retaining device held in engagement with the hammer by centrifugal force, substantially as set forth.

50 2. In a fuse for projectiles, the combination of a fuse-body, and an inertia-operated hammer movably supported in the fuse-body, with a hammer-retaining device held in engagement 55 with the hammer by centrifugal force for retaining the hammer in its inactive position in the fuse-body during the flight of the projectile, substantially as set forth.

3. In a fuse for projectiles, the combination of a fuse-body, a primer, a firing-pin, and a 60 spherical hammer mounted in the fuse-body and capable of sidewise or forward displacement therein to engage the firing-pin, with automatically-operated means adapted to retain the hammer in its inactive position in the

fuse-body during the flight of the projectile, 65 substantially as set forth.

4. In a fuse for projectiles, the combination of a fuse-body, a primer, a firing-pin, and a spherical hammer supported in the fuse-body and capable of sidewise or forward displacement 70 therein to move toward the firing-pin, with a hammer-retaining device operated by centrifugal force and adapted to directly engage the hammer and retain it in its inactive position during the flight of the projectile, 75 substantially as set forth.

5. In a fuse for projectiles, the combination of a fuse-body, and an inertia-operated hammer supported in the fuse-body and capable 80 of sidewise and forward detonating movement therein, with automatically-operated means adapted to retain the hammer in its inactive position in the fuse-body during the flight of the projectile, substantially as set forth.

6. In a fuse for projectiles, the combination of a fuse-body, a primer mounted in the forward or inner end of the fuse-body, a firing-pin movable longitudinally in the fuse-body, and a hammer supported in the fuse-body and capable of sidewise or forward detonating 90 movement, with an automatically-operated hammer-retaining device engaging the hammer and tending to force it rearwardly in the fuse-body to retain the hammer in its inactive position during the flight of the projectile, 95 substantially as set forth.

7. In a fuse for projectiles, the combination of a fuse-body formed with a hammer-receiving cavity and a central concave hammer-seat, and a hammer movably supported in said 100 cavity and designed to move therein longitudinally or sidewise of the projectile, with automatically-operated means adapted to retain the hammer in its central rearward position in said concave seat of the fuse-body during 105 the flight of the projectile, substantially as set forth.

8. In a fuse for projectiles, the combination of a fuse-body, and a hammer supported in a cavity in the fuse-body and movable forwardly 110 therein, with automatically-operated means adapted to engage the hammer and force it backwardly into its rearward position in the fuse-body and retain it in said position during the flight of the projectile, substantially as set 115 forth.

9. In a fuse for projectiles, the combination of a fuse-body formed with a hammer-receiving cavity having a central concave seat at its rear end, and a hammer supported in the cavity of the fuse-body and movable forwardly 120 therein, with automatically-operated means adapted to force the hammer backwardly and retain it in its central rearward position in the concave seat during the flight of the projectile, substantially as set forth.

10. In a fuse for projectiles, the combination of a fuse-body, a primer, a firing-pin, and

5 a hammer supported in the fuse-body and adapted to operate the firing-pin by its side-wise or forward displacement in the fuse-body, with a hammer-retaining device operated by centrifugal force and adapted to retain the hammer in its inactive position during the flight of the projectile, substantially as set forth.

10 11. In a fuse for projectiles, the combination of a fuse-body, and a hammer movably mounted in the fuse-body, with a hammer-retaining device loosely engaging the hammer and constructed and arranged to be actuated by the centrifugal force to exert upon the 15 hammer a restraining force proportional to the square of the velocity of rotation of the projectile, substantially as set forth.

12. In a fuse for projectiles, the combination of a fuse-body, an inertia-operated hammer movably mounted in the fuse-body, and means for normally retaining the hammer in its inoperative position while the projectile is at rest, with an automatically-operated hammer-retaining device adapted to engage the 25 hammer and force it rearwardly into inactive position in the fuse-body and retain it in said position during the flight of the projectile, substantially as set forth.

13. In a fuse for projectiles, the combination of a fuse-body, a hammer movably supported in the fuse-body, means for retaining the hammer in its inactive position while the projectile is at rest, and a centrifugally-operated hammer-retaining device adapted to engage the hammer and tend to force it rearwardly into its inactive position during the flight of the projectile, substantially as set forth.

14. In a fuse for projectiles, the combination of a fuse-body, a hammer movably supported in the fuse-body, and automatically-released means for retaining the hammer in its inactive position while the projectile is at rest, with a centrifugally-operated hammer-retaining device mounted in the fuse-casing and adapted to directly engage the hammer and tend to force it rearwardly into its inactive position during the flight of the projectile, substantially as set forth.

15. In a fuse for projectiles, the combination of a fuse-body, a hammer movably supported in the fuse-body, a hammer-securing pin, and a plurality of centrifugally-released devices arranged to lock the securing-pin in hammer-securing position while the projectile

is at rest, with centrifugally-operated hammer-retaining means adapted to engage the hammer and hold it in its inactive position during the flight of the projectile, substantially as set forth. 60

16. In a fuse for projectiles, the combination of a fuse-body, and a hammer movably supported in the fuse-body, with an arm or weight movably mounted in the fuse-body and adapted to be actuated by centrifugal force to engage the hammer and hold it in its inactive position during the flight of the projectile, substantially as set forth. 65

17. In a fuse for projectiles, the combination of a fuse-body, and a hammer movably supported in the fuse-body, with a laterally-movable arm or weight freely mounted in a recess or cavity in the fuse-body and adapted to be actuated by centrifugal force to engage the hammer and hold it in its inactive position during the flight of the projectile, substantially as set forth. 70

18. In a fuse for projectiles, the combination of a fuse-body, and a hammer movably supported in the fuse-body, with a plurality of arms or weights movably mounted in the fuse-body and adapted to be actuated by centrifugal force to engage the hammer and retain it in its inactive position during the flight of the projectile, substantially as set forth. 75 80

19. In a fuse for projectiles, the combination of a fuse-body, a hammer movably supported in the fuse-body, with a spring-arm supported in the fuse-body and engaging the hammer, and a weight acting upon said spring-arm under the influence of centrifugal force to cause the spring-arm to retain the hammer in its inactive position during the flight of the projectile, substantially as set forth. 90

20. In a fuse for projectiles, the combination of a fuse-body, a hammer movably supported in the fuse-body, a primer, a combined firing-pin and hammer-securing pin, and centrifugally-operated controlling means adapted to normally lock said firing and securing pin in its hammer-securing position, with centrifugally-operated hammer-retaining means adapted to hold the hammer in its inactive position during the flight of the projectile, substantially as set forth. 95 100

HENRY P. MERRIAM.
